FREIGHT CAR APPLIANCES

Edgar Benatar, Bloomfield, N. J.

Application June 24, 1933, Serial No. 677,412

2 Claims. (Cl. 105—285)

This invention relates to freight car appliances and has for its main object and feature the production of a device for controlling the opening movement of the hopper door of a hopper-car.

5 In the accompanying drawing the invention is disclosed in a concrete and preferred form in which

Fig. 1 is a view in side elevation of a freight car with my appliance in position;

10 Fig. 2 is an enlarged sectional view of the appliance showing it in position between the two hoppers; and

Fig. 3 is a cross-sectional view substantially on the plane of line 3—3 of Fig. 2.

15 Railroad cars of the hopper type are usually provided with two hoppers on the underside for the discharge of coal or other material. In the drawing these two hoppers are indicated at 10 and 11. At least one of the inclined sides of 20 each hopper constitutes a hinged door 12 through which the material is discharged, and the problem here involved is to control the extent of opening of the hopper door.

In the form of the invention here disclosed, 25 the device is constructed as follows: a support is provided composed of two members 13 and 14 that are in telescoping relation, and carried at each end of the device is a head 15 or 16 having a self-adjusting mounting here conveniently shown as a ball and socket joint 17. One or more abutment members 18 and 19 may be employed which may take the form of sleeves that can be adjusted lengthwise of member 13 and clamped in position by bolts 20.

30 It will now be understood that the device can be placed between opposed surfaces of adjacent hoppers, at least one of which surfaces is a door, and that the heads can be adjusted to such angular position as to cause their bearing members 22 to lie substantially parallel to said surfaces. Usually these surfaces are provided with projections as 21 on which bearing members 22 of the heads may rest, or they may be permanently attached to the surfaces. Abutment member 18 is now adjusted so as to be a certain distance away from the end of member 13. Thereafter the door of one of the hoppers is released, and the weight of the material in the car causes the door to swing open. In so 35 doing the door will change its angular position, and the head that engages said door will adjust

itself to a corresponding position. Also member 13 or 14 will yield until abutment member 18 strikes the end of 13 thereby permitting the hopper door to open a given distance, but preventing opening movement thereof beyond said 5 distance. If it is now desired to increase the opening movement of the door, the bolt that locks abutment member 18 in position may be slightly released so as to permit a sliding movement, with frictional resistance, of the parts to 10 take place, after which the bolt of 18 is again tightened. Or abutment member 19 can be adjusted on 14 and secured in position, after which the bolt of 18 can be released thereby allowing 14 to slide through 18 until 18 and 19 come in 15 contact. If both opposed surfaces of adjacent hoppers are doors, the doors may be sequentially or simultaneously opened as each head of the appliance is self-adjusting independently of the other. It will further be understood that instead of placing the appliance between opposed surfaces of adjacent hoppers, it may be placed with one head against the hopper door and with 20 its other end against a railroad tie.

I claim:

1. The combination with the opposed hopper doors of a hopper car; of an extensible support reaching from door to door, the support being in its extended position when the doors are closed and moving into a withdrawn position under 30 the influence of the weight of the door when either or both of said doors are opened; a self-adjusting mounting on said support to respond to various angular positions of the doors; and means to limit the extent of withdrawal of said 35 support.

2. The combination with two opposed surfaces, at least one of which is a hopper door, that opens by gravity, of a hopper car; of a detachable extensible support for the door abutting 40 against and reaching from surface to surface, the support being in its extended position when the door is closed and moving into a withdrawn position under the influence of the weight of the door when the latter is opened; a self-adjusting 45 mounting at each end of said support to respond to various angular positions of the surfaces; and means to limit the withdrawal of said support.

EDGAR BENATAR. 50
